UNITED STATES PATENT OFFICE.

EDWARD C. WALKER AND FREDERICK J. BRINKER, OF ST. LOUIS, MISSOURI, AS-SIGNORS TO NATIONAL LEAD COMPANY, OF NEW YORK, N. Y., A CORPORATION OF NEW YORK.

BARREL-CLOSING PROCESS AND MECHANISM.

Application filed May 18, 1923. Serial No. 639,876.

To all whom it may concern:

Be it known that we, EDWARD C. WALKER and FREDERICK J. BRINKER, citizens of the United States, and residing at St. Louis, 5 State of Missouri, have invented the new and useful Improvement in Barrel-Closing Processes and Mechanism, of which the following is a specification.

This invention relates to a process and 10 mechanism for closing barrels and similar containers, and is applied more particularly to the closing of containers constructed of sheet metal and the like.

Such materials as white lead are shipped 15 in metal containers, including metal barrels. These containers must be of strong and rugged construction since the material has considerable weight and is in fluid or semi-fluid form. Such containers must also be 20 securely sealed in such a way as to avoid the seal being accidentally broken during the handling of the barrel and by the yielding or distortion thereof.

One of the objects of this invention, therefore, 25 is to provide a method of sealing such barrels and containers which shall provide a tight seal and one securely locked against accidental breaking of the seal.

Another object of this invention is to provide 30 mechanism for effectively sealing such a container.

Further objects will appear from the detail description taken in connection with the accompanying drawing, in which:

35 Figure 1 is a view showing part of a sealed container with the sealing mechanism in place thereon;

Fig. 2 is an enlarged fragmentary view 40 showing the sealing mechanism in the process of forming a seal; and

Fig. 3 is a partial plan view of Fig. 1.

Referring to the accompanying drawing, 45 1 designates the body of the barrel or container, the upper part of which is flared outwardly so as to form a seat 2 for the barrel head. Beyond the seat 2 the metal is formed over a pair of reinforcing strips 3 so as to provide a bead 4 along the upper rim of the barrel. The barrel head is also formed of 50 sheet metal with a dished body 5 and an up-turned tapering flange 6 adapted to fit the tapered seat 2 on the barrel. The upper part of the flange 6 is turned outwardly to provide a top flange 7 adapted to rest on 55 the rim of the barrel when the head is in

place. The tapered flange 6 may be formed to have a snug fit in the seat 2 so that by forcing the head down into said seat until the flange 7 engages the rim of the barrel a tight seal is provided. 60

In order to secure the head in place after it has been forced home, a ring 8 is provided having an upper flange 9 adapted to rest upon the flange 7 and shaped to fit the same, and an outer vertical flange 10 adapted to 65 slip over the head 4 on the rim of the barrel. When the ring 8 is first applied the flange 10 is straight as shown in Figure 2. This flange is then curled under the bead 4 as shown in Figure 1. 70

In order to turn under the flange 10 as above described the following mechanism may be provided. A frame consisting of a horizontally disposed cross-bar 11 and having an up-standing projection 12, is provided with a bearing pin 13 adapted to carry a roll 14 having a concave face 15 adapted to run on the ring 8 when in place on the barrel. The opposite end of the bar 11 is bifurcated having a pair of downwardly extending arms 16 (only one of which is shown in Figure 1). The arms 16 reach over the rim of the barrel and extend downwardly from the top, each being provided at its extremity with a bearing pin 17 85 carrying a roll 18 adapted to take under the bead 4 so as to hold the bar 11 in position across the top of the barrel during the operation. Pivoted at 19 on the upper end of the projection 12 is a lever having a 90 downwardly extending portion 20 reaching to a point near the rim of the barrel and then bent substantially at right angles so as to provide a horizontally extending manipulating handle 21. Near the bend of the lever a concave roll 22 is carried on a bearing pin 23. The arrangement is such that when the ring 8 has been applied and forced down on the head, the closing mechanism may be applied by engaging the rolls 18 under the 100 rim on one side and resting the roll 14 on top of the ring 8. The roll 22 will then be in a position to rest against the extended free edge of the flange 10 as illustrated in Figure 2. By now applying a downward pressure on the end of the arm 21, the operator may turn the flange 10 inwardly under the bead 4 and by turning the entire mechanism around the barrel head the rolls 14 and 22 will roll along the ring 8, the roll 110

22 turning under the free edge of the flange 10 as it progresses. During this movement the rear end of the bar 11 will be guided by the rolls 18 which run around under the 5 rim or bead 4. When the turning in of the flange 10 has been completed, the barrel will have the appearance shown in Figure 1.

Thus a simple and convenient method for 10 closing barrels is provided. The barrel end is shaped so as to form a snug taper fit with the barrel head. The locking ring 8 may then be applied over the barrel head and secured to the barrel by crimping the flange 10 as described. The mechanism for accomplishing this purpose is very simple. The 15 frame 11 is quickly and easily applied and rolls on the barrel rim, being guided by the rolls 18 and 14 while the roll 22 effectively turns under or crimps the flange 10 under 20 the bead 4 so as to secure the barrel head in place.

It is obvious that various changes may be 25 made in details of construction without departing from the spirit of this invention; it is, therefore, to be understood that this invention is not to be limited to the specific details shown and described.

Having thus described the invention, what 30 is claimed is:

80 1. In the art of closing barrels, the process comprising placing the head on the barrel end, slipping a closed flanged ring over the barrel end and on the head thereon, and simultaneously rolling the ring flange inwardly against the barrel while the top of the ring is being rolled downwardly against the head.

40 2. A barrel closing hand tool comprising a roll adapted to run on the barrel rim to press endwise thereagainst a roll adapted to run against the side of the barrel, and means for pressing said rolls together.

45 3. A barrel closing hand tool, comprising a roll adapted to run on the barrel rim to press endwise thereagainst a roll adapted to run against the side of the barrel, supports for said rolls, a pivoted connection between said supports, and a hand lever on one of said supports.

4. A barrel closing hand tool, comprising 50 a frame adapted to take over the barrel end and having a roll adapted to run on the barrel rim and a lever pivoted to said frame and having a roll adapted to run against the side of the barrel. 55

5. Barrel closing mechanism, comprising a frame adapted to take over the barrel end and having a roll adapted to run on the barrel end and a roll adapted to take under the barrel end, and a lever pivoted to said 60 frame and having a roll adapted to run against the side of the barrel.

6. Barrel closing mechanism, comprising a frame adapted to take over the barrel end and having a guide roll and a pressure roll 65 adapted to run on the barrel end, and a lever pivoted to said frame and having a co-operating pressure roll adapted to run against the side of the barrel.

7. Barrel closing mechanism, comprising 70 a frame adapted to take over the barrel end and having a guide roll running thereon, a pressure roll on said frame adapted to run on the barrel rim, a lever pivoted on said frame, and a crimping roll on said lever 75 adapted to take under the barrel rim.

8. Barrel closing mechanism, comprising a frame adapted to take over the barrel end and having a guide roll running thereon, a pressure roll on said frame adapted to run 80 on the barrel rim, a lever pivoted on said frame, a crimping roll on said lever adapted to take under the barrel rim, and means for pressing the rim between said pressure and crimping rolls. 85

9. Barrel closing mechanism, comprising a frame adapted to take over the barrel end and having a guide roll running thereon, a pressure roll on said frame adapted to run on the barrel rim, a lever pivoted on said frame, and a crimping roll on said lever 90 adapted to engage the side of the barrel transversely of said pressure roll.

In testimony whereof we affix our signatures this 21st day of March, 1923.

EDWARD C. WALKER.
FREDERICK J. BRINKER.
